WIRING DEVICE

Arthur E. Bromley, Bridgeport, Conn., assignor to The Bryant Electric Company, Bridgeport, Conn., a corporation of Connecticut

Application March 25, 1955, Serial No. 496,664

17 Claims. (Cl. 339—164)

My invention relates generally to electrical wiring devices and, more particularly, to a new and improved wiring device having screwless terminals for electrically connecting such devices together and to a source of electrical power.

Although in principle my invention is applicable to a wide variety of wiring devices, it is more particularly suited for the small low voltage devices, such as household wiring devices where the use of standard electrical connecting means such as terminal screws represents a substantial percentage of the cost of the complete wiring device. Some prior attempts to obtain screwless terminals for such devices have required separate wire engaging means to accommodate various sizes of electrical conductors or have been of such intricate construction so as to be impractical. Still other prior screwless terminals also have required the housing of the wiring device to be formed in an intricate manner so as to properly support a part of the screwless terminal, which construction has added to the cost of producing such devices.

Accordingly, one object of my invention is to provide a new and improved wiring device having improved and simplified means for making electrical connections thereto.

A more specific object of my invention is to provide a new and improved wiring device which utilizes a one-piece spring clamp to engage various sizes of electrical conductors and which has integral means for locating the clamp within the device.

Another specific object of my invention is to provide a new and improved wiring device having a one-piece wire engaging clamp for use in screwless terminals which is fabricated from spring metal which is slotted to form two legs.

A further object of my invention is to provide a new and improved wiring device with screwless terminals having a housing of simplified construction.

Another object of my invention is to provide a new and improved wiring device having a housing of simplified construction with self-locating screwless terminals of simplified construction therein.

These and other objects of my invention will become more apparent upon consideration of the following detailed description of a wiring device constructed in accordance with the principles of my invention, when taken in connection with the attached drawings, in which:

Figure 1 is a side elevational view of a duplex receptacle constructed in accordance with the principles of my invention with one portion of the wire thereof in cross section;

Fig. 2 is a top plan view of the bottom portion of the receptacle shown in Fig. 1 showing located therein one elongated terminal and a pair of spring clamps adjacent thereto and omitting the other elongated terminal and its associated clamps for clarity;

Fig. 3 is a cross-sectional view of the receptacle shown

2

in Fig. 1 taken substantially along the line III—III of Fig. 2 but including the portions omitted therein; and

Fig. 4 is an enlarged perspective view of a spring clamp constructed in accordance with my invention.

Figs. 1 to 3 illustrate a receptacle which is constructed in accordance with the principles of my invention which comprises an upper housing 2, a lower housing 4, an electrical terminal 6 located within the housings 2 and 4, a pair of spring clamps 5 and 5' adjacent the electrical terminal 6 and a yoke 8 for mounting the entire assembly. The particular construction of housing 2 and the cooperative structure of yoke 8 whereby the housing 2 and yoke 8 are secured together does not form a part of this invention but may be of any satisfactory construction similar to that more completely shown, described and claimed in the copending application, entitled Wiring Device, Serial No. 463,771, filed October 21, 1954 of O. L. Taylor, now Patent No. 2,865,010 and which has been assigned to the same assignee as this invention.

Both the housings 2 and 4 are formed from any suitable insulating material, preferably from a molded insulating material which may readily be provided with the necessary external and internal structure as hereinafter described. Housing 4 is symmetrical about its longitudinal axis and formed so that a terminal 6 may be located at each side thereof. For clarity of this description, in Fig. 2, only one terminal 6 is shown located in housing 4, however, two such terminals 6 are normally employed in the assembled receptacle as shown in Fig. 3. Each electrical terminal 6 is formed from any suitable good electrical conducting material, such as copper or brass. Spring clips 5 and 5' are formed from any suitable resilient material, such as spring steel, to operate in a manner as hereinafter described, and yoke 8 may be formed from any suitable material which has sufficient structural strength, such as sheet steel.

Lower housing 4 (Fig. 2) comprises an approximately rectangular base 28 having upwardly extending formed side walls 30 which in turn are joined together at each end of the base 28 by upwardly extending end walls 32. Lower housing 4 is provided with a central, longitudinally extending barrier 18 on substantially its longitudinal center line which extends between the end walls 32 so as to form a longitudinally extending chamber 3 between each side wall 30 of housing 4 and the barrier 18. It will also be noted (Fig. 3) that the sides 10 of barrier 18 are substantially perpendicular to the base 28.

Each terminal 6 comprises an elongated longitudinally extending arm 34 which terminates at each of its ends in integral U-shaped portions 42 which are formed so that their bight portions are parallel to, but longitudinally displaced inwardly from, the arm 34 and with their open ends in approximately longitudinal alignment with the arm 34. Each arm and the bight portion of the U-shaped portion 42 is provided with an upwardly extending blade 41, each of which is bent inwardly toward the middle of the U-shaped portion 42 so as to form a T-shaped opening therewithin. If desired, each blade 41 may be provided with an integral angularly, upwardly and outwardly extending projection 44 for guiding the blades of an inserted connector (not shown) within the T-shaped opening.

In order to support and receive the longitudinally extending arm 34 of each terminal 6 within each chamber 3, the portion of base 28 within each chamber 3 of housing 4 is provided with a longitudinally extending groove 36 in alignment with the inner surface of the side wall 30 which has a lateral width so as to closely receive arm 34 therein. Each groove 36 terminates at each of its ends in a laterally and inwardly extending recess 45 which is of a size to closely receive a U-shaped portion

42 of terminal 6 therein. In order to support arm 34 of each terminal 6 in engagement with the inner surfaces of side walls 30, barrier 18 is provided with a pair of longitudinally spaced supports 12 which extend laterally outwardly from each side 10 thereof toward groove 36 adjacent thereto. The outer ends of supports 12 are spaced inwardly from the inner surface of the adjacent side wall 30 so that the arm 34 of terminal 6 may be received therebetween. A further support 14 is provided on each side of barrier 18, on approximately the lateral center line of housing 4, each of which extends laterally outward from the sides 10 toward the inner surface of the side walls 30, in the same manner as supports 12. By such construction each terminal 6 may easily be inserted from the open side of housing 4 so that the lower edge of its arm 34 enters groove 36, and its arm itself is supported against the inner surface of side walls 30 by the outer ends of supports 12 and 14. At the same time U-shaped portions 42 of each terminal 6 are located in appropriate recesses 45. As can readily be appreciated, since housing 4 is preferably a molded part, a slight taper may easily be provided on the inner surface of end walls 32 to force the outer arms of the U-shaped ends 42 toward each other to slightly bias the ends of terminal 6 towards each other. If desired, additional integral locating means may be provided on the inner surface of base 28 and on the barrier 18 to properly locate the various parts of terminal 6 within the chamber 3 of housing 4, as is more fully described in the above-identified copending application. Grooves 36, supports 12 and 14, and recesses 45 may easily be provided in housing 4 by well known forming operations.

Referring to Fig. 4, it will be noted that a spring clamp 5 constructed in accordance with the principles of my invention comprises a one-piece member formed from a single plate having an upwardly extending generally rectangular back 50 which is divided into substantially two equal parts by means of an upwardly extending slot 52. If desired, in order to relieve the stress concentration at the end of slot 52, it may be provided at its upper end with a suitable enlarged opening such as a transversely extending oblong opening 54 which has its upper edge closely adjacent the upper edge of the back 50. By so dividing back 50, one portion thereof may be easily deflected with relation to the other portion. If desired, the upper portion of back 50 may be bent angularly outward therefrom to form a flange 51 which provides additional rigidity thereto. The lower edge of each spaced portion of back 50 is provided with an integral outwardly extending rectangular leg, which legs are approximately of equal length and are located on the same side of back 50 as the flange 51. As shown, one leg 56 extends substantially perpendicular to back 50, while the other leg 58 extends angularly upward towards back 50 so as to form a generally V-shape therewith. The free edge of leg 58 is provided with an offset inwardly projecting semi-circular offset 60 for wire engaging purposes, as discussed hereinafter. Inasmuch as such construction is quite simple, spring clamps 5 may inexpensively be fabricated by simple blanking and bending operations. As hereinafter indicated, a second spring clamp 5' is also used in my device which is substantially identical to spring clamp 5, and accordingly, like parts have the same reference numeral.

Referring again to Fig. 2, housing 4 is also symmetrical about its lateral center line so that the supports 12 and support 14 on each side of barrier 18 form a pair of longitudinally adjacent chambers 40 adjacent each arm 34 of the terminals 6. Although as indicated only two spring clamps are shown (Fig. 2) located in one pair of adjacent chambers 40, each chamber 40 is formed so that a spring clamp may be closely received therein.

Each chamber 40 is formed so that a spring clamp 5 or 5' may be located therein with its leg 56 engaging the inner surface of base 28, and with its back 50 en-

gaging the longitudinally extending side 10 of barrier 18 forming a part of the particular chamber 40 in which the spring clamp 5 or 5' is located. Each support 12 is spaced from its adjacent support 14 so that the sides of each spring clamp 5 or 5' are closely adjacent the adjacent sides thereof, whereby spring clamp 5 or 5' is supported against any substantially longitudinal movement within chambers 40. In this regard, it will be noted that each of the spring clamps 5 or 5' when located within a chamber 40 is formed so that legs 56 thereof are adjacent the support 14. Such arrangement of spring clamps 5 and 5' is for the purpose of providing additional space between the conductors leading to the assembled device. It is obvious, however, that such location of legs 56 of spring clamps 5 and 5' requires these two spring clamps to be fabricated with the legs 56 and 58 interchanged thereon. Thus, the spring clamp 5 shown in Fig. 4 is only adapted to be located in the upper right and lower left-hand chambers 40 of Fig. 2. The spring clamp 5', which is identical to the spring clamp 5 previously described in all respects except that the legs 56 and 58 are interchanged with relation to back 50, is adapted to be located in the upper left and lower right-hand chambers 40 of Fig. 2. By so providing oppositely formed spring clamps 5 and 5', housing 4 may be formed so as to be symmetrical about its lateral center line with relation to openings 62 and 64 in base 28, as hereinafter described. As will become apparent, either a single-type spring clamp 5 or 5' could be located in all of the chambers 40 by merely relocating certain openings 62 and 64 in base 28 so as to be cooperable with the legs 58 thereof as hereinafter described.

Once spring clamps 5 and 5' and terminals 6 have been located as indicated in housing 4, the upper housing 2 with yoke 8 secured thereto, as previously indicated, is then secured to the lower housing 4. In assembling housing 2 to housing 4, the underside of housing 2 must obviously be formed to cooperate with the various parts of the upper surface of housing 4 and to permit yoke 8 to extend longitudinally outward from each end thereof. The side walls of housing 2 are also formed to engage the side walls 30 of housing 4 so as to form a complete housing structure with housing 4. Reference is again made to the above-identified copending application as illustrative of a similarly constructed upper housing. As shown in Fig. 1, housing 2 is provided with upwardly extending longitudinally spaced projections 66 which are provided with a pair of laterally spaced slots 68 (only one of which is shown) whereby the prongs of an inserted connector (not shown) may engage the blades 41 at one end of each terminal 6. Housing 2 is also provided with a central opening 80 between projections 66 for exposing a portion of yoke 8 which portion is provided with a threaded opening 82, whereby a standard face plate (not shown) may be secured to the yoke 8 by means of a threaded screw. In order to accommodate such a screw, the barrier 18 of housing 4 is provided (Fig. 2) with an enlargement having a circular recess 70 which is aligned with opening 82. The upper edge of recess 70 is formed to engage the lower edge of housing 2 so as to centrally support housing 2. Barrier 18 is also provided with an enlargement having an opening 72 at each longitudinal side of recess 70 which extends entirely through barrier 18 and terminates in an enlarged recess 74 on the underside of base 28. Yoke 8 is provided with a threaded opening 76 in alignment with each opening 72 when the device is assembled. Thereafter, housing 2 may be secured to housing 4 by inserting machine screws 78 through openings 72 so that their threaded end engages the threaded openings 76 in yoke 8 in alignment therewith and so that the heads thereof engage the inner surface of the recesses 74. It will be noted that other suitable means may be employed to secure housing 2

to housing 4 such as described in the above-identified copending application.

If desired, only one securing means 78 and cooperating opening 72 need be provided for screw 78 or other securing means to secure housings 2 and 4 together, as shown in the above-identified copending application. If desired, one support 14 may be provided with a sloping surface 92 which is cooperable with a downwardly extending projection (not shown) on the underside of housing 2 so as to permit housing 2 to be assembled to housing 4 in only one relative manner. Or if desired, recesses 94 may be provided in end walls 32 of housing 4 adjacent diagonally opposed chambers 44 which are cooperable with downwardly extending projections (not shown) on the underside of housing 2 so as to also permit housing 2 to be assembled to housing 4 in only one relative manner.

Referring to Figs 2 and 3 it will be noted that the portion of base 28 in each chamber 40 closely adjacent each support 12 is provided with openings 62 and 64 so that they are directly below the angularly extending legs 58 of spring clamps 5 and 5'. Openings 62 are for the purpose of receiving a bare electrical conductor therein and accordingly are preferably circular in form. Since electrical connections are to be made to terminals 6, they are located adjacent the terminal 6 so that their outermost edge (Fig. 2) is in alignment with the inner edge of its cooperable terminal 6. An opening 64 is located between each opening 62 and the adjacent side 10 of barrier 18 for wire releasing purposes, and accordingly a longitudinally (Fig. 2) elongated slot configuration is preferred whereby a suitable blunt instrument such as a screwdriver blade may be inserted therethrough. Openings 62 and 64 may have other configurations for accomplishing such purposes. Offsets 60 of spring clamps 5 and 5' are located in alignment with openings 62, and accordingly, they are displaced from the center of leg 58 toward its outer side.

As shown in Fig. 3, the inner surface of housing 2 above each of the chambers 40 is provided with a flat surface 86 which extends substantially perpendicularly outwardly from the sides 10 of barrier 18 and which is spaced upwardly from the inner surface of base 28 of housing 4 so as to engage the upper free edges of the flange 51 in each of the chambers 40, whereby spring clamps 5 and 5' are held against displacement upwardly toward the upper housing 2. The inner surface of housing 2 above each of the chambers 40 is also provided with a projection 88 between each side 10 of barrier 18 and the side wall 30 of housing 4 adjacent thereto, which extends downwardly from surface 86 toward the base 28 of housing 4. As shown each projection 88 is provided with a sloping surface 90 which extends from its free end angularly upward and outwardly toward housing 2 and are located so as to be in the path of motion of legs 58 when they are deflected by an inserted conductor so as to limit the upward movement of legs 58. Inasmuch as projections 88 need only cooperate with legs 58 of spring clamps 5 and 5' they need only extend longitudinally within chambers 40 approximately the width of legs 58. If desired, however, projection 88 may extend substantially the entire distance between the opposed surfaces of supports 12 and 14.

As has been indicated, receptacles constructed in accordance with the principles of my invention are best suited for household or similar use where low alternating current voltages are customarily supplied. Although such wiring systems do not have a polarity in the technical sense of the word, it is necessary to keep each side of the supply line independent throughout the system as one side of the line is customarily grounded. Thus each terminal 6 within the receptacle must be connected to different sides of the supply line. In making such electrical connections, a bare electrical conductor (not shown) is initially inserted into any open-

ing 62 in the base 28 of housing 4 until the conductor engages the free edge of the wire engaging leg 58 of the adjacent spring clamp 5 or 5' at the offset 60. By exerting an additional force upon the conductor the upper end of the conductor will enter offset 60 and force the leg 58 upwardly toward the adjacent side 10 of barrier 18, so that the conductor will slip past the offset 60 in leg 58 upwardly toward housing 2. Once the conductor has slipped past leg 58, the free edge thereof is resiliently forced against the conductor to hold the conductor within the housing 4 against arm 34 of adjacent terminal 6, due to the resiliency of the material from which spring clamp 5 or 5' is made. Inasmuch as leg 58 is angularly disposed with relation to the inserted conductor, any reverse force applied to the conductor will tend to jam the leg 58 into further engagement with the conductor, thereby preventing the conductor from being removed from the housing 4. It is also obvious that the force exerted by the leg 58 upon the conductor is dependent upon the force necessary to initially deflect the leg 58, and accordingly it is a matter of design as to the material used for the spring clamps 5 and 5' and the position of legs 58 of spring clamps 5 and 5' with respect to the conductor. Once the conductor has been so inserted within the housing 4, it is desirable that the portion of the conductor located outside the housing 4 be provided with insulation (not shown) to prevent an electrical hazard. As legs 58 of spring clamps 5 and 5' are deflected, various sizes of commercially available conductors may be held by the spring clamps 5 and 5', inasmuch as the larger diameter wires will cause the leg 58 to be deflected a greater amount. It is obvious, of course, that extremely large conductors would not be satisfactory for such service, and such are prevented from being inserted by the limitations of the size of openings 62. Further, the engagement of the upper end of legs 58 of spring clamps 5 and 5' with the sloping surfaces 90 in projections 88 prevent the legs 58 from being deformed to a point where permanent deformation occurs.

In order to release the conductor from the leg 58 of a spring clamp 5 or 5', it is only necessary to insert a blunt instrument, such as a screwdriver, within the adjacent opening 64 in the base 28 of lower housing 4, and engage the undersurface of leg 58 and force it upwardly toward housing 2, whereby the clamping force on the conductor is removed and the conductor may easily be withdrawn. Inasmuch as each spring clamp 5 or 5' is thus accessible, the conductors may be removed individually from their various positions within the housing 4.

Thus, it will be noted that by providing a simply formed integral structure in the upper and lower housings of a receptacle a wire clamp of my construction may easily be assembled therein without requiring any additional fastening means for securing the wire clamp to the housing. Also, as my wire clamp is of simplified form it may easily be produced in an inexpensive manner. Although I have shown and described one particular modification of my invention in accordance with the patent statutes, I am aware that modifications thereof are possible. Accordingly, it is desired that my invention be accorded a scope consistent with the spirit of its broad principles.

I claim as my invention:

1. An electrical receptacle comprising, an elongated hollow housing formed from an insulating material and having a base surface joining opposite sides thereof, elongated terminals located in fixed relationship along the inner surface of said opposite sides of said housing, respectively, said housing having integral means extending laterally inwardly from said base surface to form a pair of longitudinally spaced U-shaped walls adjacent each terminal with their open sides facing the terminal

adjacent thereto, one-piece springs closely fitting between the arms of each of said walls, respectively, each of said springs comprising a back portion engaging the inner surface of the bight portion of said walls and a first lateral arm extending from the back portion to engage said base surface of said housing between the arms of said walls and extending between said bight portion and the terminal adjacent thereto so that said spring is substantially non-movably located within the chamber defined by said walls and said base surface, each of said springs having a second arm extending angularly laterally from said back portion adjacent said base surface with its free end located closely adjacent the inner surface of the terminal adjacent thereto, said back portion formed to prevent the transmitting of stresses from said second arm to said first arm, and an opening in said base surface to the exterior of said housing below each of said second arms whereby an electrical conductor may be inserted therethrough between each of said free ends and its adjacent terminal.

2. A wiring device comprising, an insulating support having portions extending laterally outwardly to form at least one U-shaped wall, at least one terminal mounted on said support having at least a part thereof extending across the open side of said wall, a one-piece spring located between the arms of said wall comprising a back portion engaging the inner surface of the bight portion of said wall and a first arm engaging the surface of said support between the arms of said wall and extending between said bight portion and said part of said terminal adjacent thereto to substantially prevent motion of said back portion away from the bight portion of said wall, said spring having a second arm extending angularly upwardly from said back portion adjacent the support and with its free end located closely adjacent said part of said terminal adjacent thereto, an opening in said support below said second arm whereby an electrical conductor may be inserted therethrough between said free end and its adjacent terminal, a cover of insulating material secured to said support having a portion thereof extending over the back portion of said spring, and said back portion of said spring being of a height so as to be closely adjacent said portion of said cover whereby said spring is restrained from upward movement between said arms of said wall.

3. A wiring device comprising, an insulating support having portions extending laterally outwardly to form at least one U-shaped wall, at least one terminal mounted on said support having at least a part thereof extending across the open side of said wall, a one-piece spring located between the arms of said wall comprising a back portion engaging the inner surface of the bight portion of said wall and a first arm engaging the surface of said support between the arms of said wall and extending between said bight portion and said part of said terminal adjacent thereto so that said spring is located within the chamber formed by said U-shaped wall so as to be non-rotatable in a plane at an angle to said wall, said spring having a second arm extending angularly upwardly from said surface and outwardly from said back portion with its free end located closely adjacent said part of said terminal adjacent thereto, an opening in the support below said second arm whereby an electrical conductor may be inserted therethrough between said free end and its adjacent terminal, a cover of insulating material secured to said support so that a portion thereof extends over the back portion of said spring, said back portion of said spring being of a height so as to be closely adjacent said portion of said cover whereby said spring is restrained from upward movement between said arms of said wall, and a projection extending downward from said portion of said cover located between said arms of said wall to limit the deflection of said second arm of said spring.

4. A wiring device comprising, an insulating support having at least one recess therein with at least one pair of

opposed substantially parallel walls, a terminal secured to said support having at least a part thereof extending across the inner surface of one of said parallel walls of said recess, a one-piece spring clamp formed from a resilient material having a back portion located in engagement with the other of said parallel walls and being of a length so as to be closely received between the sides of said recess so that said spring is restrained from movement within said recess parallel to said walls, said spring having a locating arm in engagement with the base of said recess extending outwardly from said back portion toward said part of said terminal and with its free end adjacent thereto so that said spring is restrained from movement transversely between said parallel walls of said recess, said spring having an engaging arm spaced from said locating arm and extending angularly outward from said back portion toward said part of said terminal and with its free end adjacent thereto, said free end of said engaging arm being located above the base of said recess, and an opening in said support located so that an electrical conductor may be inserted therethrough between said free end of said engaging arm and said part of said terminal.

5. A wiring device comprising, two cup-shaped insulating members which are secured together to form a hollow housing, at least one open-sided recess in the interior of one of said insulating members having its open side extending toward the open side of said one insulating member, said recess having at least one pair of opposed substantially parallel side walls, a terminal mounted in said housing having at least a part thereof extending across the inner surface of one of said parallel walls of said recess, a one-piece spring clamp formed from a resilient material located in said recess and having a back portion located in engagement with the other of said parallel walls and being of a length so as to be closely received between the sides of said recess so that said spring clamp is restrained from movement within said recess parallel to said walls, said spring clamp having a locating arm in engagement with the innermost surface of said recess extending outwardly from said back portion toward said part of said terminal and with its free end adjacent thereto so that said spring clamp is restrained from movement transversely between said parallel walls of said recess, said spring clamp having an engaging arm spaced from said locating arm and extending angularly outward from said back portion toward said part of said terminal and with its free end adjacent thereto, said free end of said engaging arm being located above said innermost surface of said recess, a projection extending inwardly from the innermost surface of the other of said insulating members having its free end closely adjacent the outermost edge of said back portion of said spring clamp so that said spring clamp is restrained from substantial movement toward said other insulating member, an opening in said one insulating member located so that an electrical conductor may be inserted therethrough between said free end of said engaging arm and said part of said terminal.

6. A wiring device comprising, an insulating support having a laterally outwardly extending terminal secured thereto, an abutment extending laterally outward from said support and spaced from a part of said terminal so as to be approximately parallel thereto, a one-piece spring clamp formed from a resilient material having an elongated back portion engageable with the surface of said abutment facing said part of said terminal and a first leg in engagement with said support and extending between said abutment and said part of said terminal with its free end adjacent said part of said terminal so that said spring clamp is restrained from movement therebetween, projections extending laterally outwardly from said support located at opposite ends of said back portion, respectively, so that said spring clamp is restrained from movement therebetween, said spring clamp having a second leg adjacent said first leg extending angularly between said abut-

ment and said part of said terminal with its free end adjacent said part of said terminal and above said support, and an opening in said support located so that an electrical conductor may be inserted therethrough between the free end of said second leg and said part of said terminal.

7. A wiring device comprising, an insulating support, a terminal secured to said support so as to extend outwardly therefrom in one direction, a one-piece spring having a resilient leg extending from a point on said support spaced from said terminal angularly outwardly from said support and toward a portion of said terminal with the free end thereof being adjacent to said portion of said terminal, an opening in said support located adjacent said portion of said terminal so that an electrical conductor may be inserted therethrough between said free end of said leg and said portion of said terminal, said support including means for maintaining said spring at the aforesaid position including an outwardly extending wall at the aforesaid point in spaced opposed relation to said terminal, said spring having an integral angularly extending portion seated on said wall and joined at its outer end to another angled portion including one leg seated on said support and another leg seated against said wall, said support also having outwardly extending portions at opposite sides of said spring preventing undesired movement of the spring, and means engaging the outer end of the leg which is seated against said wall for preventing movement thereof away from said support.

8. A wiring device comprising, an insulating support, a terminal mounted on one side of said support so as to extend outwardly therefrom, an abutment also extending outwardly from said one side of the support in spaced opposed relation to said terminal, a spring clamp formed of a strip of resilient material having a back seated against the opposed wall formed by said abutment, a clamping leg projecting from the inner edge of said back adjacent said support angularly outwardly from said support to a point adjacent one portion of said terminal, a positioning leg also projecting from the inner edge of said back toward said one portion of said terminal parallel to and seated on said one side of said support and terminating adjacent said one portion of said terminal to substantially prevent motion of said back away from said wall, means mounted on said support engaging the outer edge of said back, and an opening through said support adjacent said one portion of the terminal so that an electrical conductor may be inserted therethrough and between the free end of the clamping leg and said portion of the terminal.

9. A wiring device comprising, an insulating support, a terminal mounted on one side of said support so as to extend outwardly therefrom, an abutment also extending outwardly from said one side of the support in spaced opposed relation to said terminal, a spring clamp formed of a strip of resilient material having a back seated against said abutment, a clamping leg projecting from the inner edge of said back adjacent said support angularly outwardly from said support to a point adjacent one portion of said terminal, a positioning leg also projecting from the inner edge of said back parallel to and seated on said one side of said support, said legs being spaced apart and said back having a slot extending from a point at its inner edge located between said legs to a point adjacent its outer edge, means mounted on said support engaging the outer edge of said back, and an opening through said support adjacent said one portion of the terminal so that an electrical conductor may be inserted therethrough and between the free end of the clamping leg and said portion of the terminal.

10. A wiring device comprising, an insulating support, a terminal mounted on one side of said support so as to extend outwardly therefrom, an abutment also extending outwardly from said one side of the support in spaced opposed relation to said terminal, a spring clamp

formed of a strip of resilient material having a back seated against said abutment, a clamping leg projecting from the edge of said back adjacent said support angularly outwardly from said support to a point adjacent one portion of said terminal, a positioning leg also projecting from the inner edge of said back parallel to and seated on said one side of said support, a flange on the outer edge of said back, means mounted on said support engaging the flange on the outer edge of said back, and an opening through said support adjacent said one portion of the terminal so that an electrical conductor may be inserted therethrough and between the free end of the clamping leg and said portion of the terminal.

11. A wiring device comprising, an insulating support, a terminal mounted on one side of said support so as to extend outwardly therefrom, an abutment also extending outwardly from said one side of the support in spaced opposed relation to said terminal, a spring clamp formed of a strip of resilient material having a back seated against said abutment, a clamping leg projecting from the edge of said back adjacent said support angularly outwardly from said support to a point adjacent one portion of said terminal, a positioning leg also projecting from the inner edge of said back parallel to and seated on said one side of said support, means mounted on said support engaging the outer edge of said back, an opening through said support adjacent said one portion of the terminal so that an electrical conductor may be inserted therethrough and between the free end of the clamping leg and said portion of the terminal, a second opening through said support beneath said clamping leg for the insertion of a tool to engage and deflect said clamping leg away from said terminal to release an inserted conductor, and stop means secured to said support above said clamping leg to limit deflection of the latter.

12. A one-piece spring clamp formed from a strip of resilient material comprising, a substantially flat back having a slot extending laterally from one side but terminating short of the opposite side thereof so as to form two substantially parallel spaced legs, a resilient substantially planar locating arm extending angularly outwardly from the outer end of one of said legs, and a resilient substantially planar engaging arm extending angularly outwardly from the outer end of the other of said legs and forming a more acute angle with said back than said locating arm, whereby said engaging arm may be resiliently deflected with respect to said locating arm.

13. A one-piece spring clamp formed from a strip of resilient material comprising, a substantially flat back having a slot extending laterally from one side but terminating short of the opposite side thereof so as to form two substantially parallel spaced legs, a substantially planar locating arm extending angularly outwardly from the free end of one of said legs, a substantially planar engaging arm extending angularly outwardly from the free end of the other of said legs and forming a more acute angle with said back than said locating arm, said opposite side of the back being formed to have an angularly extending flange thereon, whereby said engaging arm may be resiliently deflected with respect to said locating arm and said flange cooperates to prevent substantial distortion of said back.

14. A one-piece spring clamp formed from a strip of resilient material comprising, a substantially flat back having a slot extending laterally from one side but terminating short of the opposite side thereof so as to form two substantially parallel spaced legs, a resilient substantially planar locating arm extending substantially perpendicularly outwardly from the free end of one of said legs, a resilient substantially planar engaging arm extending angularly outwardly from the free end of the other of said legs and forming an acute angle therewith, said opposite side of the back being formed with an angularly extending flange, and said locating arm, said

engaging arm and said flange all extending outwardly from the same side of said back.

15. A wiring device comprising, an insulating support, a terminal secured to said support to extend outwardly therefrom in one direction, a one-piece spring having a resilient leg extending from a point on said support spaced from said terminal angularly outwardly from said support and toward a portion of said terminal with the free end thereof being adjacent to said portion of said terminal, an opening in said support located adjacent said portion of said terminal so that an electrical conductor may be inserted therethrough between said free end of said leg and said portion of said terminal, said support including means for maintaining said spring at the aforesaid position including a wall extending outwardly at the aforesaid point in spaced opposed relation to said terminal, said spring having another angled portion including one leg seated on said support and another leg seated against said wall, said support also having outwardly extending portions at opposite sides of said spring preventing sidewise movement of the spring, and means engaging the outer end of the leg which is seated against said wall for preventing movement thereof away from said support.

16. A wiring device comprising, an insulating support having at least one outwardly extending U-shaped wall a terminal secured to said support having at least a part thereof extending across the open ends of said wall, a one-piece spring clamp formed from a resilient material comprising a substantially flat elongated back slotted laterally from one side to form two substantially parallel spaced legs, said slot terminating adjacent the opposite side of said back, a locating arm extending substantially perpendicularly outwardly from the free end of one of said legs, an engaging arm extending angularly outwardly from the free end of the other of said legs and forming an acute angle therewith, said spring clamp being of a size to be closely received between the arms of said wall with said back engaging the bight portion thereof, said locating arm engaging said support and terminating adjacent said terminal and the free end of said engaging arm being located adjacent said part of said terminal and spaced laterally outwardly from said support when said spring

is so located between said arms of said wall; and an opening in said support located so that an electrical conductor may be inserted therethrough between said free end of said engaging arm and said part of said terminal.

5. 17. An electrical receptacle comprising, an elongated, hollow housing formed from an insulating material, elongated terminals located in fixed relationship along spaced inner surfaces of said housing, respectively, said housing having at least one integral U-shaped wall formed 10 adjacent each terminal with one side edge engaging the bottom of said housing and with the open end thereof facing the terminal adjacent thereto, one-piece springs closely fitting between the arms of each of said walls, respectively, each of said springs comprising a first portion seated on the bottom of said housing and extending from the bight portion of said walls substantially to the adjacent terminal for locating said springs between said walls to substantially prevent relative motion therebetween, a resilient second portion connected to said first portion in 15 a manner to prevent the transfer of stress from one of said portions to the other and having a free end located near the adjacent terminal, said second portion of said spring extending angularly with relation to said terminal so as to form an acute angle therewith, and an opening 20 in said housing in each of the areas thereof between each of said terminals and each of said free ends, respectively, whereby an electrical conductor may be inserted therethrough to be engaged by one of said free ends and its adjacent terminal.
